Primary Examiner—Kay H. Chin**Attorney, Agent, or Firm—**Wallenstein, Wagner & Hattis, Ltd.[57] **CLAIM**

The ornamental design for a connector for a pallet assembly, as shown and described.

DESCRIPTION

FIG. 1 is a perspective top view of a connector for a pallet assembly showing our new design;
 FIG. 2 is a top plan view of the connector;
 FIG. 3 is a bottom plan view of the connector;
 FIG. 4 is a right elevation view of the connector with the left elevation view being a mirror image thereof;
 and,
 FIG. 5 is a front elevation view of the connector with the rear elevation view being a mirror image thereof.
